UNITED STATES PATENT OFFICE

WILLIAM B. JASPERT, OF PITTSBURGH, PENNSYLVANIA

TILE FLOOR

Application filed February 7, 1928. Serial No. 252,536.

This invention relates to improvements in composite floors such as tile floors and the like, and it is among the objects thereof to provide a composite floor structure having a durable wearing surface of relatively hard material which is supported on the sub-floor in such a manner as to possess the characteristics of a resilient wearing surface, in the sense that it will substantially eliminate the production of sound and will be of a sound and heat insulating character.

Another object of the invention is to provide a tile floor in which the tile is secured to the supporting structure by strips of material which are interlocked with the body of the tile.

Still another object of the invention is to provide a binding strip for tile which shall be continuous, that is, in long lengths whereby the laying of tile is greatly facilitated.

Still another object of the invention is to provide means for fastening the tile locking strips in a manner to reinforce such strips and to permit securing the tile upon the foundation member.

These and other objects will become more apparent from a consideration of the accompanying drawings, in which like reference characters designate like parts and in which Fig. 1 is a view in perspective of a composite floor structure embodying the principles of this invention; Fig. 2 and Fig. 3 are similar views illustrating the tile and manner of interlocking them in accordance with the invention; Fig. 4 is a perspective view of a tile supporting member; Fig. 5 is a cross sectional view of the tile fastening strip embodying a reinforced element; Fig. 6 is a view in perspective of a one piece strip for fastening tile; and Figs. 7 and 8 are plan views illustrating several designs to which the form of strip shown in Fig. 6 will lend itself.

Referring to Fig. 1 of the drawings, the structure therein illustrated comprises a foundation member of boards 1 which are located on joists in the usual manner, or the foundation member may comprise any suitable support to which tile may be secured.

The tile 2 is fastened on the foundation mem-

ber by strips 4 and in the preferred construction a rubber sheeting 3 or other resilient material is interposed between the tile and foundation member. The tile is secured by the strips 4 which may be nailed or fastened by screws in any suitable manner, and in addition, the successive tiles are secured against displacement by an interlock effected through the binding strips 4 which consists of the cooperative engagement of tongues 5 formed on the edge of the tile with grooves 6 formed in the binding strips 4. An alternate form of interlock is illustrated in Fig. 3 in which the binding strip 4 is provided with tongues 8 and the tile with grooves 7.

The binding strip 4 is formed of a resilient material such as rubber which is of sufficient strength to prevent the displacement of the tile and which is of such physical characteristics that the individual tiles are isolated whereby the production of sound is materially lessened.

Where tile is laid on rubber sheeting 3 the production of sound resulting from impact with the floor is very remote with the result that a floor made of tile having all the desired wearing characteristics, such as hardness, strength and proper decorative effect, can be utilized without obtaining the detrimental effects resulting from the employment of tile supported in the manner heretofore practiced.

As shown in Fig. 4 the binding strips 10 and resilient supporting sheet 9 may be made in one piece by molding. Tile may be either glued or interlocked in the molded support and the latter may be fastened to the foundation in any suitable manner.

Referring to Fig. 5, a re-enforcing strip 11 is molded into the rubber strip 4 as shown, the strip 11 being of any suitable shape but preferably of a form which projects over or partially envelops the tongue element 5 of the tile which is disposed in the groove 6 of the strip, whereby a relatively rigid fastening means is provided for securing the tile to the foundation member. The strips 4 may be fastened by driving a nail 12 or screw through the re-enforcing strip 11 as illustrated.

In Figs. 6, 7 and 8 I have illustrated a form of binding strip 13 which is of zig-zag shape and provided with grooves 6 in the manner as hereinafter explained. The advantages in utilizing such a one piece strip are apparent from the illustrations in Figs. 7 and 8.

In Fig. 7 the strip 13 is laid with the convergent edges in alignment resulting in the design shown in which the tile, although surrounded by the strip on all its four sides, are theoretically contacting at their points, although practically such a design would possess the characteristics of the composite floor illustrated in Fig. 1.

15 In Fig. 8 the strips 13 have been offset to support the tile in the manner shown so that the individual tile will be surrounded by a strip on all sides and at its convergent edge precisely in the manner shown in Fig. 1.

20 By utilization of the strip as shown in Fig. 6, laying of the tile is greatly facilitated since it is obvious that a strip can be placed on a row of tile to hold the same in position and at the same time constitute a pattern or jig 25 for the laying of the next row of tile whereby an accurate spacing and placing of tile is assured.

It will be evident from the foregoing description of this invention that composite floors made in accordance therewith, possess 30 all the desired properties of decorative and serviceable flooring for dwellings and public buildings and it is particularly evident that such flooring may be constructed of practically indestructible materials.

It is further evident that the resilient supporting sheeting and strip materials may be made of relatively inexpensive grades of rubber such as reclaimed rubber which is available 40 in commercial quantities and which can be readily molded to the shape and dimensions of the form of strip required.

Although several embodiments of the invention have been herein illustrated and described, it will be obvious to those skilled in the art that various changes may be made in the details of construction and in the arrangement of the several cooperating parts without departing from the principles herein set forth.

I claim:

1. A composite floor comprising a wearing 55 surface of tile secured to a foundation member by molded binding strips of zig-zag shape, said strips having irregular contours for engagement with complementary shaped edges of the tile to form a mechanical interlock therewith.

60 2. A composite floor comprising in combination a foundation member, a wearing surface of tile and preformed strips for interlocking with the edges of said tile and for fastening said tile to the foundation member, 65 said strips having reinforcing material em-

bedded therein which overlaps the interlocking edges of adjacent tile.

3. A composite floor comprising in combination a foundation member, a wearing surface of tile having edge faces of irregular contour and strips of resilient material having reinforcing material embedded therein and having their tile engaging edges complementary in shape to the edge of said tile for interlocking engagement therewith, the reinforcing material of said strips extending beyond the interlocking edge of the tile and strip members.

In testimony whereof, I have hereunto set my hand.

WILLIAM B. JASPERT.
